UNITED STATES PATENT OFFICE.

LONGLEY LEWIS SAGENDORPH, OF PHILADELPHIA, PENNSYLVANIA.

DESIGN FOR A SIDING-PLATE FOR BUILDINGS.

SPECIFICATION forming part of Design No. 20,825, dated June 9, 1891.

Application filed April 17, 1891. Serial No. 389,382. Term of patent 14 years.

To all whom it may concern:

Be it known that I, LONGLEY LEWIS SAGENDORPH, a citizen of the United States, residing at Philadelphia, in the county of Philadelphia, State of Pennsylvania, have invented and produced a new and original Design for Metallic Sidings for Buildings, of which the following is a specification, reference being had to the accompanying drawings.

10 Figure 1 is a face view of a portion of a metallic siding-plate, illustrating my design. Fig. 2 is a cross-section on the dotted line 2 2 of Fig. 1. Fig. 3 is a cross-section, on an enlarged scale, taken through a portion of the 15 plate and two of the longitudinal grooves.

My design consists of a metallic plate having a series of continuous longitudinal grooves and alternating cross-grooves intersecting said longitudinal grooves, each of said cross 20 and longitudinal grooves having therein a beaded corrugation A, the outer face of which is convex with the outer face of the plate, as shown. The sides *a* of each groove are at substantially right angles to the face of the 25 plate and are slightly rounded at the angular points *a'*, as more clearly shown in Fig. 3.

The alternating cross-corrugations intersect with adjacent longitudinal corrugations, as shown, said corrugations being located within the aforesaid longitudinal and cross 30 grooves and convex with the outer face of the sheet.

The general effect of my design is to represent raised brick or stone work, the corrugations A simulating the mortar-line, while the 35 angles *a'* simulate the edges of the brick.

What I claim is—

The design for metallic siding herein set forth, consisting of continuous longitudinal grooves and alternating cross-grooves terminating in said longitudinal grooves, each of said grooves having therein a central beaded corrugation A, the alternating cross-corrugations terminating in the longitudinal corrugations, said corrugations being convex with 40 the outer surface of the siding-plate, substantially as set forth.

LONGLEY LEWIS SAGENDORPH.
